IMPACT CRUSHER

Edgar B. Symons, Hollywood, Calif., assignor to
Nordberg Manufacturing Company, Milwaukee,
Wis., a corporation of Wisconsin

Application January 17, 1938, Serial No. 185,278

11 Claims.

(Cl. 83—46)

My invention relates to an improvement in impact crushers and has for one purpose the provision of such a crusher in which the particles will be crushed with a minimum of slippage on the face of the impact members.

Another purpose is the provision of improved bearing or supporting means for the rotor of such a crusher.

Another purpose is the provision of improved impact members for such a crusher.

Another purpose is the provision of improved spout means for such a crusher.

Another purpose is the provision of improved means for securing the impact members in position.

Other objects will appear from time to time in the course of the specification and claims.

The present application is a continuation in part of my co-pending application Serial No. 710,592 which was filed February 10, 1934, now Patent No. 2,110,851.

I illustrate my invention more or less diagrammatically in the accompanying drawings wherein:

Figure 1 is a vertical transverse section;

Figure 2 is a detail;

Figure 3 is a section on the line 3—3 of Figure 1;

Figure 4 is a section on the line 4—4 of Figure 1;

Figure 5 is a section on line 5—5 of Figure 4; and

Figure 6 is a detail.

Like members are indicated by like symbols throughout the specification and drawings.

Referring to the drawings, 1 generally indicates any suitable supporting structure or element which may for example be a concrete or masonry foundation. Mounted thereon I illustrate two horizontal parallel I-beams 2, the lower flanges 3 of which rest upon the foundation 1 and the upper flanges 4 of which serve as supports for bearing boxes generally indicated as 5. Each such bearing box has positioned therewithin a bushing or circumferential member of rubber or the like 6 in which is an inner member 7 which receives the outer ball or roller race 8 within which are the rollers 9. 10 is an inner race associated with the shaft generally indicated as 11. Said shaft has an outer extension 12 at one end on which is mounted any suitable drive pulley or pulleys 13.

The shaft includes a central portion 14 herein indicated as slightly enlarged in relation to the outer ends of the shaft which penetrate the

bearing races 10. Keyed to the shaft 14 by the key 15 is the hub or body portion generally indicated as 16 which has an outer generally cylindrical portion 17 connected to it for example by a web or intermediate portion 18. It is provided also with a plurality of outer extensions 19 having faces 20 herein indicated as somewhat rearwardly inclined.

At each end of the member 16 and abutting against the edges of the member 17 are rings 21, the structure being tied together for example by bolts 22 with nuts 23, the parts being appropriately apertured to receive them. Each such ring 21 is shown as having a plurality of apertures 24, each such aperture having an inclined wedge 15 face 25. Seated against the faces 20 of the members 19 are impact members 26, each such impact member having at each end an end flange 27. Preferably the impact member so formed is flat and of uniform thickness throughout, including the flanges 27. The parts are so proportioned that the flanges 27 penetrate the apertures 24. In order to lock the impact members in position I employ wedge members as shown for example in Figure 2, each one of 25 which includes a wedge portion 28 adapted to seat in the aperture 24 and having a wedge face 29 opposed to the face 25.

It will be understood that as the rotor rotates centrifugal force will tend to move the wedge 30 outwardly with the face 29 sliding against the face 25 of the ring 21. The result will be to force the opposite side 30 of the wedge forcibly against the face of the adjacent flange 27 of the impact member, as shown for example in Figure 35. Additional means for holding the wedge elements in position are shown and include an outer portion 31 having an elongated aperture 31a through which passes any suitable bolt or securing member 32 with its nut 33. Positioned within the space formed by the rings 21 are removable wear plates 34. If desired, each bolt 32 may pass through one of these plates and may thereafter perform the unitary service of securing the plate 34 in position as well as cooperating with the portion 31 of the wedge 28. Additional bolts may also be employed as shown at 35 in Figure 4, with any suitable securing nuts 36.

The housing proper may be formed of opposite 30 generally vertical side walls 37, 38 and may extend downwardly through the foundation 1 to provide any suitable discharge portion 39 herein shown as having a plurality of inclined discharge surfaces 40, 41. Limiting ledges 42 extend in 55

wardly from the side members 37, 38 and terminate closely adjacent the outer edges of the members 21. The side elements 37, 38 are provided with apertures of sufficient size to permit the shaft end portions 11 to extend outwardly therethrough with sufficient clearance to prevent metal to metal contact at any position of the shaft and the clearance is sufficient for example to provide for whatever compression takes place of the yielding members 6.

A generally vertical feed spout 43 is indicated for example in Figure 1 having one edge 44 terminating closely adjacent the path of movement of the impact members and conforming to 15 or secured to the arcuate housing member 45 which also conforms closely to the path of the beaters and may be hinged if desired as at 46 and bolted or otherwise secured in position. The opposite edge of the spout as at 47 is cut substantially away from the path of movement of the impact members, the two edges being connected by inclined side edges 48. It will be understood that the edge 44 is in the direction of approach of the impact members so that after 20 the impact takes place ample space is left between the path of the impact members and the edge 47 for the escape of the impacted particles.

I may employ any suitable normally fixed impact members for receiving the centrifugally 30 pelled particles. I illustrate for example a plurality of removable plates 49, 50 which may be mounted in any suitable manner as for example on backing members 51 which may be bolted in position as by the bolts 52 with the nuts 53 at 35 each end thereof.

It will be realized that whereas I have described and illustrated a practical and operative device, nevertheless many changes may be made in the size, shape, number and disposition of parts without departing from the spirit of my invention. 40 I therefore wish my description and drawings to be taken as in a broad sense illustrative or diagrammatic, rather than as limiting me to my precise showing.

45 The use and operation of my invention are as follows:

The material to be reduced is gravitally dropped, preferably in an unconsolidated stream, down the spout 43. The impact member is rotated at sufficient speed in relation to the acceleration by gravity of the particles to give crushing impacts of adequate force. The spacing of the impact members about the rotor is also so related to the speed of rotation of the 50 impact members and to the speed of feed as to provide a non-slipping crushing impact to each particle whereby there is a minimum wear of the impact members.

The impact members are readily applied and 60 removed and the wedge securing means has the important result of causing the speed of rotation of the rotor itself to tighten up the wedges in response to the centrifugal outward movement of the wedges 28 in the apertures 24. The wedges 65 can easily be loosened by loosening the nuts 33 and the inner wear plates 34 can readily be removed and replaced.

I find it advantageous to make the members 26 of such a shape as to permit their ready reversal 70 since there is a maximum of wear in the upper portion of the impact member. After a given impact member has become somewhat worn it can readily be reversed, preferably before being worn down too far. The result is a substantial 75 increase in economy as the manganese steel

of which such members are generally made is an expensive metal and the metal cost of crushing is a substantial factor in crushing costs and thus in the efficiency of a crushing device.

I claim:

1. In an impact crusher, a rotor, and means for rotating it, said rotor including a hub having terminal portions of reduced diameter and an intermediate portion of substantially greater diameter, generally annular end plates mounted on and surrounding the hub portions of reduced diameter, and laterally abutting against the hub portion of increased diameter, apertures in said plates, and unitary wear taking plates abutting against said intermediate hub portion and including unitary lugs extending endwise outwardly into said apertures, said intermediate hub portion including radially extending members having supporting faces adapted to receive and support the rear faces of said wear taking plates. 20

2. In an impact crusher, a rotor, and means for rotating it, said rotor including a hub having terminal portions of reduced diameter and an intermediate portion of substantially greater diameter, generally annular end plates mounted on and surrounding the hub portions of reduced diameter, and laterally abutting against the hub portion of increased diameter, apertures in said plates, and unitary wear taking plates abutting against said intermediate hub portion and including unitary lugs extending endwise outwardly into said apertures, said intermediate hub portion including radially extending members having supporting faces adapted to receive and support substantially the entire rear faces of said 35 wear-taking plates, and locking members including portions penetrating said apertures and opposed to said lugs.

3. In an impact crusher, a rotor, and means for rotating it, said rotor including a hub having 40 terminal portions of reduced diameter and an intermediate portion of substantially greater diameter, generally annular end plates mounted on and surrounding the hub portions of reduced diameter, and laterally abutting against the hub portion of increased diameter, apertures in said plates, and unitary wear taking plates abutting against said intermediate hub portion and including unitary lugs extending endwise outwardly into said apertures, said intermediate hub portion including radially extending members having supporting faces adapted to receive and support substantially the entire rear faces of said 50 wear-taking plates, and locking members including portions penetrating said apertures and opposed to said lugs, said locking members being 55 centrifugally movable toward locking position.

4. In an impact crusher, a rotor, and means for rotating it, said rotor including a hub having 60 terminal portions of reduced diameter and an intermediate portion of substantially greater diameter, generally annular end plates mounted on and surrounding the hub portions of reduced diameter, and laterally abutting against the hub portion of increased diameter, apertures in said plates, and unitary wear taking plates abutting against said intermediate hub portion and including unitary lugs extending endwise outwardly into said apertures, said intermediate hub portion including radially extending members having 65 supporting faces adapted to receive and support substantially the entire rear faces of said wear-taking plates, and locking members including portions penetrating said apertures and opposed to said lugs, said locking members being 70 75

75 increase in economy as the manganese steel

centrifugally movable toward locking position, the portions of said locking members which penetrate said apertures, and the apertures themselves, having opposed inclined faces adapted, in response to the centrifugal movement of said locking members, to urge said locking members laterally against said lugs.

5. In an impact crusher, a rotor including a shaft, and bearing means therefor, means for rotating the shaft, a body member surrounding and extending radially outwardly from said shaft, said body member having a plurality of generally radial projections, end rings at each end of said body member, and impact plates mounted on the faces of said radial projections, said impact plates having unitary lugs extending outwardly through said rings, and means for securing said lugs in position in relation to said rings.

6. In an impact crusher, a rotor, bearing means therefor, and means for rotating it, said rotor including an axially extending body portion, a plurality of generally radial projections extending outwardly therealong, rings at each end of said body portion, and unitary impact plates mounted on the faces of said projections, and having integral lugs extending into said rings, said radial projections having supporting faces adapted to receive and support substantially the entire rear faces of said unitary impact plates.

7. In an impact crusher, a rotor, bearing means therefor, and means for rotating it, said rotor including an axially extending body portion, a plurality of generally radial projections extending outwardly therealong, rings at each end of said body portion, and unitary impact plates mounted on the faces of said projections, and having integral lugs extending into said rings, and centrifugal locking members opposed to said lugs, said radial projections having supporting faces adapted to receive and support substantially the entire rear faces of said unitary impact plates.

8. In an impact crusher, a rotor, and means for rotating it, the rotor including a body member having generally radial projections, a plurality of impact members mounted on and circumferentially spaced about said body member, and seated on said projections, said projections having supporting faces adapted to receive and support sub-

stantially the entire rear faces of said impact members, and means for securing said impact members in place, including centrifugally actuated wedges, movable in relation thereto, opposed to portions thereof.

9. In an impact crusher, a rotor, and means for rotating it, the rotor including a body member having generally radial projections, a plurality of impact members mounted on and circumferentially spaced about said body member, and seated on said projections, said projections having supporting faces adapted to receive and support substantially the entire rear faces of said impact members, and means for securing said impact members in place, including centrifugally actuated wedges, movable in relation thereto, opposed to portions thereof.

10. In an impact crusher, a rotor and means for rotating it, said rotor including a central portion having a plurality of generally radial outward projections, generally annular apertured end plates against which the ends of said radial projections abut, apertures in said end plates, and unitary wear-taking plates abutting against said radially extending projections and including unitary lugs extending endwise outwardly into the apertures of said end plates, said radially extending projections having supporting faces adapted to receive and support the rear faces of said wear-taking plates throughout substantially their entire area.

11. In combination with the rotor of an impact crusher having a generally radial projection with a supporting face and plate locking means, a wear-taking plate abutting against such supporting face throughout substantially the entire rear face of the plate, the plate including a body portion having a front impact taking face and a rear supporting face, the two said faces being substantially parallel, said body portion being generally rectangular and having a securing lug of substantially the same thickness as the plate and lying in the plane of the plate, projecting outwardly from each end thereof, substantially in the middle of such ends, and in cooperative relationship with the plate locking means.

EDGAR B. SYMONS. 50
